UNITED STATES PATENT OFFICE.

HERMAN A. GRIESINGER, OF CHICAGO, ILLINOIS, ASSIGNOR TO THOMAS CUSACK COMPANY, OF CHICAGO, ILLINOIS, A CORPORATION OF NEW JERSEY.

ELECTRICALLY-ILLUMINATED SIGN.

Application filed June 25, 1923. Serial No. 647,429.

To all whom it may concern:

Be it known that I, HERMAN A. GRIESINGER, a citizen of the United States and a resident of Chicago, in the county of Cook and State of Illinois, have invented certain new and useful Improvements in Electrically-Illuminated Signs; and I do hereby declare that the following is a full, clear, and exact description thereof, reference being had to the accompanying drawings, and to the letters of reference marked thereon, which form a part of this specification.

This invention relates to improvements in electrically illuminated signs and consists of the matters hereinafter described and more particularly pointed out in the appended claims.

The invention relates especially to what is known as a double face sign with letters or characters on the two opposite faces, and with means within the sign body for illuminating both faces. The object of the invention is to produce a sign of the kind in which a reflector may be cheaply and economically provided on the interior of the sign body so as to act efficiently for both faces of the sign, and wherein the reflector is so constructed that the lamps for the illumination of the sign characters on the opposite faces of the sign may be supported in such manner as to be readily gotten at for removal or renewal.

These and other advantages of the invention will appear more fully as I proceed with my specification.

Referring now to the drawings:—

Fig. 1 is a view representing in perspective a sign embodying the invention with some of the letter plates removed to show the inner construction of the sign.

Fig. 2 is a view representing a horizontal section through the sign in the plane of the lamps which are used for its illumination.

Fig. 3 is a view representing a vertical section through the sign body in a plane indicated by the line 3—3 of Fig. 2.

Fig. 4 is a perspective view of a part of the reflector plate used in the sign.

The novel improvements comprised in the invention may be embodied in any type of double face sign with transparent, translucent opal glass or other familiar types of sign character plates, depending upon the purpose for which the sign is to be used and the taste or desires of the user of the sign.

In the example of the invention illustrated herein, the sign is shown with the familiar glass letter plates which may be of opal glass and which may be flat or may have raised characters, with the characters outlined or blocked out by stencil plates or otherwise, in a familiar manner.

Referring now more particularly to that embodiment of the invention illustrated in the drawings:—10 indicates the sign body which is a metal box of any familiar construction, with opposed, vertical faces 11, 11, which contain the sign characters. 12 indicates the glass letter plates (as illustrated, each bearing a raised character 13) and 14 indicates the stencil plates, there being in this case, a stencil plate for each character. The details of construction in this respect may be of any familiar or well known kind and form no part of the present invention.

15 indicates a partition wall located in a vertical position substantially in the median plane of the sign body. Said partition wall comprises a plurality of vertically disposed panels 16, with the adjacent panels located in narrowly spaced, vertical planes and connected together by vertical webs 17 extending substantially at right angles to said panels. The panels 16 and webs 17 provide together, a succession of channel-like vertically disposed, open chambers, with the alternate chambers facing in opposite directions.

In the webs 17, and preferably in the horizontal median plane of the sign body, are located in line, a series of holes 18. The webs 17 are made wide enough in a horizontal direction to allow space for holes 18 which are of sufficient diameter to provide support for lamp sockets 19, which are secured therein, in any familiar well known manner. 20 indicates lamps which are severally mounted in the sockets. In each panel 16, in horizontal alignment with the associated lamp 20, is provided an opening 21, substantially of the outline of the lamp bulb.

The opposite faces of the panels 16 are constructed or treated so as to provide bright reflecting surfaces 22, 23, and said surfaces, as will be readily apparent, reinforce by their reflecting character, the light directly transmitted from the lights through the transparent or translucent character bodies when the sign is illuminated. Each lamp illuminates to some extent, both faces of the

sign, mainly that face which is opposed to the open channel in which the lamp is located, and to some extent, the opposite face of the sign which is opposed to the back of said channel. The direct light which passes from each lamp through the opening in the panel back of it, is reinforced by the reflecting surface 22 of said panel, while the reflecting surface 23 on the opposite side of said panel or that nearest the lamp, reinforces the direct illumination given by the said lamp in the face of the sign on the same side of the reflector as the said reflecting surface 23.

Manifestly, the lamp globes, by reason of the arrangement described, are readily gotten at when the sign body is opened, either by removing one of the letter plates and stencils or otherwise, as may be provided in any familiar manner, for gaining access to the interior of the sign.

The partition extends preferably from top to bottom of the sign body and also from end to end of the same, being secured in place at its top and bottom edges and at its ends in any familiar manner, as by soldering or otherwise.

I claim as my invention:

1. In an electrically illuminated sign, the combination of a sign body having glass letter plates upon opposite sides thereof, a reflecting partition in said sign body midway between said letter plates, said partition comprising a plurality of vertically disposed reflecting panels extending from the top to the bottom of the body and providing a succession of channel-like, vertically dis-

posed open chambers, and lamp sockets carried by said partition and so positioned thereon that the associated lamps are arranged in axial alignment with at least one lamp in each chamber. 40

2. In an electrically illuminated sign, the combination of a sign body having glass letter plates upon opposite sides thereof, a reflecting partition in said sign body midway between said letter plates, said partition comprising a plurality of vertically disposed reflecting panels, with adjacent panels located in spaced vertical planes and connected together by transversely disposed webs, providing a succession of channel-like vertically disposed open chambers, with alternate chambers facing in opposite direction, and lamp sockets carried by said webs, 45 so that the associated lamps are arranged at least one in each chamber, each panel having an opening therein back of the lamp. 55

3. A reflecting partition for use in a double face electrically illuminated sign comprising a plurality of vertically disposed panels with adjacent panels located in narrowly spaced, vertical planes, said panels being connected together by vertical webs extending substantially at right angles to said panels, said panels and webs providing together, a succession of channel-like vertically disposed, open chambers, with alternate chambers facing in opposite directions. 60 65

In testimony that I claim the foregoing as my invention, I affix my signature this 21st day of June, A. D. 1923. 70

HERMAN A. GRIESINGER.
